UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

FOLDING CARRIAGE.

No. 857,971.

Specification of Letters Patent.

Patented June 25, 1907.

Application filed February 12, 1907. Serial No. 366,971.

To all whom it may concern:

Be it known that I, ARTHUR J. ADAMS, a citizen of the United States, residing at Chicago, in the county of Cook and State of Illinois, have invented a new and useful 5 Folding Carriage, of which the following is a specification.

My invention relates particularly to folding baby carriages, doll carriages, go-carts 10 and the like; and my primary object is to provide improved means for locking the wheel supports in an upright position.

The invention may be employed to peculiar 15 advantage in connection with folding carriages of the type disclosed in my Patent No. 789,310, granted May 9, 1905.

The invention is illustrated in the accompanying drawings, in which:—

Figure 1 represents a side elevational view 20 of a folding carriage constructed in accordance with my present improvements; Fig. 2, a broken perspective detail view of one of the connections between a pair of wheel supports; Fig. 3, a similar view illustrating a modification 25 of said connection; Fig. 4, an enlarged section taken as indicated at line 4 of Fig. 6 and showing a locking device employed in connection with a pair of folding links forming a connection between a pair of wheel 30 supports; Fig. 5, a section taken as indicated at line 5 of Fig. 4; Fig. 6, a plan section taken as indicated at line 6 of Fig. 1; Fig. 7, a similar 35 plan section, showing the wheel supports and wheels folded inwardly and upwardly; Fig. 8, a front elevational view of the running gear frame; Fig. 9, a similar view 40 showing one side pair of the wheel supports and wheels folded inwardly and upwardly; and Fig. 10, a similar view showing all of the

The frame, A, may be of any suitable construction. It comprises, as shown, side members, a, and cross members, a¹. The side members are equipped with clips or stampings, a², with which the upper ends of the wheel supports are joined by longitudinally 55 extending pivots, a³, in a manner now well understood.

The two wheel supports at each side of the frame are joined in a pair by longitudinally-extending bars, a⁴, which connect the lower 60 ends of said supports, so that each side pair of wheels will swing as a unit. The lower ends of the wheel supports have connected therewith the out-turned spindles, a⁵, upon which are journaled the wheels, a⁶.

The link mechanism A², comprises in preferred form a folding front cross member, a⁷, a folding rear cross member, a⁸, and a longitudinal connecting link, a⁹. Each folding cross bar comprises a pair of links, a¹⁰, a¹¹, 75 which are joined together at the median longitudinal plane of the running gear frame by a vertical pivot, a¹²; short, twisted links, a¹³, joined to the outer extremities of the links a¹⁰, a¹¹, by vertical pivots, a¹⁴; and angle-form clips, a¹⁵, having transversely-extending arms, a¹⁶, joined by horizontal, longitudinally-disposed pivots, a¹⁷, to the outer ends of the links, a¹³, and having longitudinally-disposed arms, a¹⁸, securely fastened by means 85 of rivets, a¹⁹, to the wheel supports, A¹, some distance above the lower ends thereof. The links, a¹⁰, a¹¹, preferably comprise flat bars which are disposed in a horizontal plane 90 when the wheel supports are in the upright position; and the short links, a¹³, preferably comprise flat bars which are given a quarter twist to adapt their ends to conform to the members with which they are connected.

The link, a⁹, preferably comprises a flat bar 95 whose ends are pivotally connected with the pivots, a¹², so that the link, a⁹, occupies the median longitudinal plane, as will be clearly understood from Fig. 6. For the purpose of securing the links in the position shown 100 in Fig. 6 and locking the wheel supports in an upright position, I equip one of the links, preferably the front link, a¹⁰, with a housing or clip, a²⁰, in which works a U-shaped lock-slide, a²¹, against which presses a spring, 105 a²², confined between the slide and the opposite end of the loop or clip, a²⁰. The slide, a²¹, has down-turned end-flanges, a²³, which

329,336 filed August 6th, 1906.

embrace the edges of the bar, a^{10} , and are adapted to engage the projecting end, a^{24} , of the corresponding bar, a^{11} . This will be clearly understood from Fig. 4. Said projecting end, a^{24} , is beveled or rounded, as indicated at a^{25} , so that when the links are swung from the position shown in Fig. 7 to the position shown in Fig. 6 by the operation of swinging the wheels to their vertical position, the locking member or slide, a^{21} , will be automatically retracted and will then automatically return under the force of its spring to effect locking connection.

From the foregoing detailed description, the operation of the wheel-support-securing mechanism will be readily understood.

When it is desired to fold the wheels laterally inwardly from the position shown in Fig. 6 to the position shown in Fig. 7, this may be accomplished by releasing the locking member, a^{21} , from engagement with the extension, a^{24} , of the front link, a^{11} , whereupon one lateral pair of wheels may be swung inwardly and upwardly and the other lateral pair of wheels may then be swung inwardly and upwardly to occupy the position shown in Fig. 10.

From the position of the cross bars, a^1 , of the running gear frame with relation to the wheel supports, A^1 , as the same appears from Fig. 1, it will be understood that the wheel supports may be folded to the position indicated in Fig. 10 without interference with the cross bars.

In the initial portion of the folding operation, the cross bars, a^7 , a^8 , are flexed upon the pivots, a^{12} , in which operation the links, a^{10} , a^{11} , swing forwardly by a species of parallel motion, about the vertical pivots, a^{14} . One lateral pair of wheels is swung upwardly, while the other pair remains, for the time being, stationary. The horizontal, longitudinal pivots, a^{17} , permit this action as will be understood from Fig. 9.

In the modification shown in Fig. 3, I have substituted a hinge, f , for the twisted link, a^{13} , and the clip, a^{15} . The hinge has a pintle, f^1 , which is disposed in a horizontal longitudinal direction. One leaf of the hinge is connected by a vertical pivot, f^2 , to the adjacent link, a^{10} , and the other leaf has its free extremity bent at right angles to the body of the leaf and secured by a rivet, f^3 , to the wheel support, A^1 . Thus, the hinge, secured as stated, affords a double pivotal or universal connection between the link, a^{10} , and the wheel support, A^1 .

The foregoing detailed description has been given for clearness of understanding only and no undue limitation is to be understood therefrom.

What I regard as new and desire to secure by Letters Patent is—

1. In a folding carriage, the combination of a running-gear frame, wheel-supports piv-

otally connected with said frame, and link-mechanism connecting said wheel-supports and comprising a foldable member having jointed connection with the wheel-supports, and means for rendering said foldable member rigid, for the purpose set forth. 70

2. In a folding carriage, the combination of a running-gear frame, a pair of wheel-supports pivotally joined to said frame at each side thereof and connected to fold together beneath the frame, and link-mechanism connecting said wheel-supports and comprising foldable members having permanent jointed connection with the wheel-supports, and means for giving rigidity to said foldable members, for the purpose set forth. 75

3. In a folding carriage, the combination of a running-gear frame, wheel-supports pivotally connected therewith, and link-mechanism connecting said wheel-supports and comprising a pair of foldable cross-members, links pivotally connected with the ends of said cross-members and pivotally connected with said wheel-supports, a link connecting said foldable cross-members, and means carried by one of said cross-members for imparting rigidity thereto in the extended position, for the purpose set forth. 80

4. In a folding carriage, the combination of a running-gear frame, a pair of wheel-supports pivotally connected with each side of said frame and connected to swing together beneath said frame, and link-mechanism connecting said wheel-supports and comprising foldable cross-members, links connecting said cross-members with said wheel-supports, a link connecting the foldable cross-members, and a spring-held locking member mounted on one of the foldable cross-members and imparting rigidity thereto in the extended position thereof. 95

5. In a folding carriage, the combination of a running-gear frame, a pair of wheel-supports pivotally connected with each side thereof, a pair of foldable cross-members, links joined by vertical pivots to said cross-members and joined by horizontal pivots to said wheel-supports, a link connecting said foldable cross-members, and means for imparting rigidity to one of said cross-members in the extended condition thereof. 110

6. In a folding carriage, the combination of a running-gear frame, a pair of swinging wheel-supports joined to each side of said frame and connected to swing together, a pair of foldable cross-members, each comprising a pair of links connected by a vertical pivot, a longitudinal link connected with said vertical pivots, links having vertical pivotal connection with the outer ends of said first-named links and having horizontal pivotal connection with said wheel-supports, and releasable means for securing one of said cross-members against flexure, for the purpose set forth. 115

7. In a folding carriage, the combination of a running-gear frame, a pair of swinging wheel-supports pivotally joined to each side of said frame, and connecting means comprising foldable cross-members, each foldable cross-member comprising a pair of links having overlapping ends joined by a vertical pivot, a longitudinal link connecting said vertical pivots, links having jointed connection with the outer ends of the links forming said foldable cross-members and with said wheel-supports, and a spring-held locking member mounted on one of the links of one of said cross-members and normally engaging the projecting end of the other link of said cross-member, for the purpose set forth.

8. In a folding carriage, the combination of a running-gear frame, a pair of connected wheel-supports pivotally connected with

each side member of said frame, a clip connected with each wheel-support, a twisted link having horizontal pivotal connection with each clip, a link having vertical pivotal connection with the inner end of each twisted link, a vertical pivot connecting the free ends of said last-mentioned links at the median longitudinal plane of the running-gear frame, the links connecting twisted links forming foldable cross-members, a longitudinal link connected with said last-named pivots, and a spring-held locking-member mounted on one of the links of a foldable cross-member and adapted to engage the adjacent link in the extended position.

ARTHUR J. ADAMS.
